UNITED STATES PATENT OFFICE.

FREDERICK R. VERNON, OF FREEPORT, NEW YORK.

KNOCKDOWN BOX.

No. 852,812.

Specification of Letters Patent.

Patented May 7, 1907.

Application filed July 10, 1905. Serial No. 268,931.

To all whom it may concern:

Be it known that I, FREDERICK R. VERNON, residing at Freeport, in the county of Nassau and State of New York, have invented 5 a new and useful Improvement in Knockdown Boxes, of which the following is a full, clear, and exact description, such as will enable others skilled in the art to which it appertains to make and use the same.

10 The object of my invention is to produce a box adapted for packing eggs and like articles, wherein the rack will form practically an integral part of the box so that when the box is set up it is completed, without the necessity of placing therein separate racks.

15 The construction is such that the rack may be folded within the box, lying flat on the bottom thereof so that the boxes may be nested, and so that many boxes, when nested, will take up only a small space. The construction is also such that if desired, the boxes may be folded flat when not in use.

20 Other objects will appear from the herein-after description.

25 The construction of the box is illustrated in the accompanying drawings which form a part of this application, and in which the same reference characters indicate the same parts in the different views.

30 Referring now to the drawings, Figure 1 is a perspective view of the box with the lid open. Fig. 2 is a vertical, longitudinal, sectional view of the box showing the rack folded on the bottom of the box. Fig. 3 is a 35 cross section showing the transverse division pieces set up with the main division piece in its horizontal position. Fig. 4 is a perspective view of one of the division pieces detached from the box. Fig. 5 is a view of the

40 blank out of which the box is made, in its open or flat position with the rack removed. Fig. 6 is a top plan view of the box showing the rack in its folded position.

45 A represents that part of the blank which forms the bottom of the box.

B represents the ends which are connected to A and which, when folded, form the ends of the box.

50 C represents pieces connected to B, and which when folded project or form flanges which extend inwardly in the box.

D represents the pieces which form the sides of the box. To the ends of these pieces are connected the interlocking ends or tabs

E and E' which interlock by the tongues e 55 fitting into the grooves or slots e' and hold the box in its set up position.

F is that part of the box forming the top of the box, and G is the overlapping edge thereof. The bottom of the box is transversely 60 cut or slit at a to form the straps A', under which the tongues of the transverse division pieces H are inserted and locked. These division pieces with the longitudinal division piece hereafter described, form the crate. 65 Formed integral with each one of these division pieces H and creased on the line h, is the tongue H'. The division piece H is slotted at h' and is provided with the opening h² into which the slot h' extends. This opening h² 70 is enlarged at h³ so that the horizontal diameter of said opening is greater than the vertical diameter. The division pieces are secured to the bottom of the box by the tongues H' passing under the straps A'. 75

J is the longitudinal division piece, each edge of which is provided with V shaped recesses or indentations j, leaving the piece forming a neck J' about the width of the vertical diameter of the openings h² in the transverse pieces. This longitudinal division piece is attached to the transverse division pieces by passing it through the slots h' edge-wise so that the neck J' fits in the opening h². 80 When the longitudinal piece is horizontal to the box, it and the transverse pieces may be folded flat on the bottom of the box, as shown in Fig. 3 of the drawing.

In order to set up the box when it is completely knocked down, the sides and ends are 85 folded and the interlocking tabs connected. The division pieces H are then raised to a vertical position, and by turning the longitudinal division piece J, 90°, or in a vertical position by turning the necks J' in the openings h², the box is set up and ready for use.

The lower edge of the division piece J resting on the bottom of the box will hold the transverse division pieces H in a vertical position 90 and prevent them from being folded in the bottom of the box so long as the said division piece J is in a vertical position. When

it is desired to nest the boxes, this division piece J is turned horizontally or parallel to the bottom of the box, when it and the transverse division pieces H can be folded flat against the bottom of the box. The sides of

105 the box are tapered to permit them to be

nested easily. When a box is to be used, it is only necessary to take one from out of the other and set up the crate by raising the division pieces until the transverse pieces are 5 in a vertical position and then turning the longitudinal division piece to a vertical position, when the crate is thus locked in position and the box is ready for use, as shown in Fig. 1 of the drawing.

- 10 The vertical diameters of the openings h^2 in the transverse pieces being about the same length as the width of the neck J' , and the horizontal openings being larger and extending in a curve to the slots h' , the longitudinal 15 division piece may be easily turned from the horizontal position to the vertical, and when in the vertical position will fit closely or bind, and this binding will assist in retaining the longitudinal division piece in its vertical position.

While I have shown and described the transverse division pieces as being secured to the bottom of the box by a tongue connection, it is apparent that this may be secured 25 by any other connection, and also the longitudinal or main division piece may be connected to the division pieces in a different manner from that specifically shown and described, and while I have shown the box provided 30 with a plurality of transverse division pieces, I may use only one such division piece so that the crate will have only four nests or compartments instead of 12 as shown in the drawing.

35 It is to be further understood that I do not confine my invention to the exact construction herein shown and described, as it is apparent that other changes may be made without departing from the spirit of my invention.

40 Having now described my invention, what I claim as new and desire to secure by Letters Patent is:—

1. A folding box having a division piece 45 connected thereto and adapted to be folded parallel to the bottom thereof or to be raised at an angle thereto, and another division piece so connected to the first division piece that it may be turned parallel to the bottom 50 of the box to permit the first mentioned division piece to be folded on the bottom or to be moved at an angle to the bottom to hold the first mentioned division piece in its raised position.

55 2. A folding box, a partition secured thereto and foldable on the bottom thereof, said partition having an opening therein, and another partition secured in said opening and adapted to be turned parallel to the bottom 60 to permit the partitions to be folded on the bottom or to be turned at an angle to the bottom to lock the partitions in their raised positions.

65 3. A folding box, a division piece having a circular opening therein secured thereto,

said division piece adapted to be raised at an angle to or folded on the bottom of the box, another division piece provided with a neck fitted and rotatable in said opening so that the said division piece may be turned parallel to the bottom of the box to permit the first division piece to be folded on the bottom or to be turned at an angle to the bottom to hold the division pieces in their raised or locked positions.

4. A folding box having a bottom, said bottom being formed with a locking device, a division piece having a tongue secured to said locking device, said division piece adapted to be raised at right angles to or folded on the bottom of the box, and also having an opening therein, another division piece provided with a neck fitted and rotatable in said opening so that it may be placed parallel to the bottom of the box to permit the first division piece to be folded on the bottom of the box or to be swung at an angle to the bottom to lock the first division piece at right angles to the bottom of the box.

5. A foldable box having a bottom, a transverse division piece connected to and adapted to be folded against the bottom, or to be raised at right angles thereto, said division piece having an opening therein and a slot extending into said opening, another division piece recessed at its edges and provided with a neck which is adapted to be inserted through the slot and into the opening in the first division piece, said neck being adapted to be turned in the said opening to permit the second division piece to be moved parallel to the bottom of the box, so that the division pieces may be folded against the bottom, or to be turned at right angles to the bottom to hold the first division piece at an angle to the bottom.

6. A folding box having a bottom, a transverse partition secured to and foldable on the bottom of the box, said transverse piece having an opening therein, one diameter of said opening being greater than the other, a longitudinal division piece connected to said transverse piece and adapted to be turned parallel to or at an angle to the bottom of the box to permit the transverse piece to be folded on the bottom of the box, or to lock said transverse piece at an angle to the bottom.

7. A folding box having a bottom, a transverse piece secured and foldable on the bottom of the box, said transverse piece having an opening therein, one of the diameters of the opening being greater than the other, a longitudinal division piece having recesses cut in the edges thereof leaving a connecting piece or neck between said recesses, the length of said neck being about the length of the shorter diameter, and said longitudinal division piece being secured to the transverse division piece by the neck fitting in the said

opening, the said longitudinal division piece being adapted to be turned parallel to the bottom to permit the pieces to be folded on the bottom of the box, or to be turned at an angle to the bottom to hold the transverse piece in its raised position.

5 In witness whereof I have hereunto set my

hand at the city of New York, county of Kings and State of New York, this 6th day of July, 1905.

FREDERICK R. VERNON.

In presence of:
F. J. VERNON,
LOUISE B. GROHS.
